12 Claims. (Cl. 323—89)

1

Our invention relates to magnetic amplifiers, and more particularly to magnetic amplifiers in which two similar transductors are provided. It is well known in the art that such transductors when connected in parallel to an alternating current source will supply equal output currents unless they are unbalanced by changing the saturations of their magnetic structures in opposite senses by means of a direct current, the "control" current. The change in the relation of the output currents is a multiple or amplification of the change in control current.

It is an object of our invention to improve the range of such magnetic amplifiers.

It is another object of our invention to enable such amplifiers to yield higher outputs.

It is also an object of our invention to render such magnetic amplifiers more efficient.

It is a further object of our invention to provide magnetic amplifiers which are compact in construction and allow a considerable reduction of metal weight in comparison to known amplifiers of similar output.

Other objects and advantages will be apparent from a consideration of the specification and claims.

According to our invention, magnetic amplifiers are improved by providing the transductors with additional windings influencing the saturations of their magnetic materials, said windings being energized by currents bearing certain relations to the currents flowing in the main windings of the transductors and serving to aid the unbalancing effect of the control current.

Our invention will be better understood from the following detailed description with reference to the accompanying drawing illustrating by way of example two embodiments of the same.

In the drawings—

Fig. 1 is a wiring diagram of a magnetic amplifier according to our invention, and

Fig. 2 is a modification of the diagram shown in Fig. 1.

Referring now to the drawings and first to Fig. 1, the amplifier shown in the diagram comprises two transductors T_1 and T_2 of similar design the principle of which is well known in the art and will be briefly explained with reference to the transductor T_1 .

The transductor T_1 comprises a magnetic structure of well-known design having two outer legs 1 and 2 and a middle leg 3 joined by yokes 4 and 5. The middle leg carries the main winding 6 which is fed from an alternating current source 7, a rectifier 8 being inserted in one of

the leads joining the source 7 to the winding 6. It will be understood that the alternating current flowing in the winding 6 depends on the state of saturation of the material of the magnetic structure. In the transductor shown in the diagram this saturation is controlled by a plurality of windings in which direct current flows. All these windings are provided in pairs, one winding of each pair on each of the outer legs 1 and 2, respectively, and each two windings belonging to the same pair are connected in series and are wound in such a manner that any alternating electromotive forces induced in them by the alternating current flowing in winding 6 will cancel each other. Altogether there are three pairs of direct current windings in the transductor as will be more fully described hereinafter.

The first pair of direct current windings 9 and 10 is fed from a direct current source 11 supplying what may be termed the "control" current. This is a current which can be varied at will by the operator or may be supplied by some controlling device of a type well known in the art. It should be noted that no alternating current will be sent back into the direct current source 11 because, as mentioned above, the control windings 9 and 10 are wound in such a sense that any electromotive forces induced in them cancel each other. It should also be noted that the windings 9, 10 are connected in series with the corresponding windings 9', 10' of the transductor T_2 so that the same "control" current controls the saturation of the material in both transductors. By means of a suitable arrangement of the windings 9', 10' it is achieved that the saturation of the material is affected in opposite senses in the two transductors so that according to the direction of the control current either the inductance of T_1 will be increased and that of T_2 decreased or that of T_1 decreased and that of T_2 increased.

The main winding 6' and the series-connected rectifier 8' of the transductor T_2 are connected in parallel to the corresponding parts of transductor T_1 .

Each transductor is provided with a second pair of windings 12, 13 and 12', 13', respectively, which will be termed "cross-reaction" windings for a reason to be explained presently. Rectifiers 14, 14' are connected across portions of the main windings 6, 6', respectively, the connections being made by means of sliding tap contacts 15, 15' and through condensers 16, 16', respectively. As will be seen from the diagram, the windings 12, 13 of transductor T_1 are energized from rec-

tifier 14' of transductor T₂, and conversely the windings 12', 13' of T₂ draw their current from rectifier 14 of T₁. Thus the current flowing in 12, 13 will be in direct proportion to the voltage at the input of rectifier 14', i. e. to that which appears across winding 6', whereas the current in 12', 13' is in direct proportion to the voltage across winding 6. It will be thus understood that there is a cross-reaction between the two transductors. A decrease of the inductance of T₁ gives an increase of the current in winding 6, the voltage across this winding is equal to the product of the intensity of the current in 6, by the impedance of this winding.

Both terms vary in opposite senses but it can be seen that impedance decreases faster than corresponding intensity increases.

A decrease in the inductance of T₁ gives a decrease in the voltage across winding 6, i. e. gives a decrease in the current that flows in the "cross-reaction" windings 12', 13' and in turn gives an increase of inductance of T₂ i. e. reduces the current in 6'. Conversely, a decrease of inductance of T₂ will increase that of T₁ which in turn will decrease the inductance of T₂ even further. Thus it will be understood that the cross-reaction windings greatly enhance the unbalancing effect of the control current. By feeding the rectifiers 14, 14' in an autotransformer connection from portions of the main windings 6, 6' through condensers 16, 16', respectively, the range and the efficiency of the device are greatly improved.

Rectifier 8 supplies to a resistance 17 a direct current i_1 proportional to the alternating current flowing in winding 6, and similarly rectifier 8' feeds a resistance 17' with a direct current i_2 proportional to the alternating current flowing in winding 6'. 17 and 17' are parts of the output circuit of the amplifier and may, for instance, be exciting windings of a reversible motor which will reverse its sense of rotation according as i_1 or i_2 is larger.

Each transductor is provided with a third pair of direct current windings, viz. 18, 19 for T₁ and 18', 19' for T₂. These windings are connected in series with one another and with the resistances 17 and 17' and also with an adjustable resistance 20, which preferably is rather large in comparison to the resistances 17 and 17'. Thus the windings 18, 19, 18', 19' will be flowed through by a current which is directly proportional to the difference $i_1 - i_2$ and the intensity of this current can be adjusted at will by a suitable adjustment of resistance 20. Bearing in mind that the windings are arranged on their respective transductors so as to affect the inductances of the latter on opposite senses, it will be understood that these windings also serve to enhance the unbalancing effect of the control current.

21 is a resistance which may be provided, if desired, in the connection between windings 19 and 18'.

The operation of the amplifier is as follows: As long as no control current is supplied, equal currents flow in 17 and 17' owing to the symmetry of the transductors T₁ and T₂. When a control current in a certain direction is supplied, the transductors will be unbalanced, the inductance of one transductor, say T₁, being decreased and that of T₂ increased, owing to the opposite effects of the windings 9, 10 and 9', 10' on the saturation of the magnetic material. Thus the currents in 6 and 6' will tend to become different and this effect is greatly enhanced by the cross-reaction between the two transductors and the effect of

the difference current flowing in the windings 18, 19 and 18', 19'. Thus a relatively large direct current will flow in resistance 17 and a much smaller one in resistance 17'. When now the direction of the control current is reversed, the current in resistance 17' will be much larger than that in 17 and it will be seen that, for instance, a motor in which 17 and 17' are exciting windings may be reversed by a relatively weak control current. It will also be understood that the current flowing in resistance 21 will reverse its direction whenever the control current is reversed.

The modification of the amplifier shown in Fig. 2 is essentially the same as that illustrated in Fig. 1 except that the rectifiers 8 and 8' are not directly connected in series with the windings 6 and 6', respectively, but through transformers. As will be seen from the diagram, the primary 22 of a transformer is connected in series to winding 6, and correspondingly primary 22' to winding 6'. The secondary winding 23 of the transformer has its circuit completed by the rectifier 8, and similarly rectifier 8' is connected to the secondary 23' of the other transformer. Resistance 20 of the amplifier according to Fig. 1 can be dispensed with here, any adjustment of the difference current being made possible by providing sliding contacts 24, 24' engaging resistances 17, 17', respectively.

The operation of the amplifier shown in Fig. 2 is exactly the same as that of the amplifier described hereinabove.

It will be appreciated that modifications of the disclosed embodiments of our invention are possible without departing from the spirit of the invention or the scope of the appended claims.

What we claim is:

1. A magnetic amplifier which comprises: a first transductor including a first saturable magnetic core structure having a first A. C. winding wound thereon, a second transductor including a second saturable magnetic core structure having a second A. C. winding wound thereon, a series connection comprising said first A. C. winding and a first impedance, a series connection comprising said second A. C. winding and a second impedance, means for connecting said series connections in parallel with a source of alternating current, a first saturation winding wound on said first core structure, means for applying a direct current through said first saturation winding proportional to the magnitude of the voltage across said second A. C. winding, a second saturation winding wound on said second core structure, means for applying a direct current through said second saturation winding proportional to the magnitude of the voltage across said first A. C. winding, a control winding wound on each of said core structures, and means for connecting said control windings to a source of variable D. C. control current so that a variation in control current causes an increase in the magnetic saturation of one core structure and a decrease in the magnetic saturation of the other core structure, all of said windings being so wound that substantially no alternating current is induced by said A. C. windings in the outputs of said control and said saturation windings.

2. A magnetic amplifier as in claim 1, and a load controlled by the difference in current flowing through said first and said second impedimentances, respectively.

3. A magnetic amplifier as in claim 2 wherein said means for applying a direct current through said first saturation winding comprises a recti-

fer connected across at least a portion of said second A. C. winding, and means connecting the D. C. output of said rectifier to said first saturation winding.

4. A magnetic amplifier as in claim 3 wherein said means for applying a direct current through said second saturation winding comprises a second rectifier connected across at least a portion of said first A. C. winding, and means connecting the D. C. output of said second rectifier to said second saturation winding.

5. A magnetic amplifier as in claim 4 including a third and a fourth saturation winding wound on said first and second core structures, respectively, in opposite electrical direction to the control winding on the same core structure, and means for passing a direct current through said third and said fourth saturation windings proportional to the magnitude of the difference in A. C. current passing through said first and said second impedances, respectively.

6. A magnetic amplifier which comprises: a first transductor including a first saturable magnetic core structure having a first A. C. winding wound thereon, a second transductor including a second saturable magnetic core structure having a second A. C. winding wound thereon, a series connection comprising said first A. C. winding and a first rectifier, a series connection comprising said second A. C. winding and a second rectifier, means for connecting said series connections in parallel with a source of alternating current, a first saturation winding wound on said first core structure, means for applying a direct current through said first saturation winding proportional to the magnitude of the voltage across said second A. C. winding, a second saturation winding wound on said second core structure, means for applying a direct current through said second saturation winding proportional to the magnitude of the voltage across said first A. C. winding, a control winding wound on each of said core structures, means for connecting said control windings to a source of variable D. C. control current so that a variation in control current causes an increase in the magnetic saturation of the other core structure, a first impedance connected across the D. C. output of said first rectifier, a second impedance connected across the D. C. output of said second rectifier, a third and a fourth saturation winding wound on said first and second core structures, respectively, in opposite electrical direction to the control winding on the same core structure, and means for passing a current through said third and said fourth saturation windings proportional to the difference in voltage across said

impedances, all of said windings being so wound that substantially no alternating current is induced by said A. C. windings in the outputs of said control and said saturation windings.

5 7. A magnetic amplifier as in claim 6, and a load connected between said first and said second impedances.

8. A magnetic amplifier as in claim 6 wherein said means for passing a current through said 10 third and fourth saturation windings comprises means connecting said third and said fourth saturation windings in series between said first and said second impedances.

9. A magnetic amplifier as in claim 1 which 15 includes a third and a fourth saturation winding wound on said first and second core structures, respectively, in opposite electrical direction to the control winding of the same core structure, a first rectifier connected across said first impedance, a first resistance connected across the D. C. output terminals of said first rectifier, a second rectifier connected across said second impedance, a second resistance connected across the D. C. output terminals of said second recti-

20 fier, and means for applying a current through said third and said fourth saturation windings proportional to the difference in potential across said first and said second resistances, respectively.

30 10. A magnetic amplifier as in claim 9, and a load connected between said first and second resistances.

11. A magnetic amplifier as in claim 10, wherein 35 said means for passing a current through said third and said fourth saturation windings comprises means connecting said third and said fourth saturation windings in series between said first and said second resistances.

12. A magnetic amplifier as in claim 11 wherein 40 in said first and said second impedances comprise transformers each having its input terminals in series with the respective A. C. winding and having its output terminals connected across the respective rectifier.
